Kossack, Lincoln, Nebr.

Application July 28, 1933, Serial No. 682,574

7 Claims.

(Cl. 305—9)

This invention relates to improvements in tractor tie rods particularly designed for track-laying or crawler type tractors. Tractors of this kind as now constructed comprise two track frames each including an endless track or track chain trained over drive sprockets at the rear and idler pulleys at the front and the frames are arranged to move or swing independently in a vertical direction at their front ends 5 to compensate for inequalities in the ground over which the tractor travels. This necessary action of the track frames of course prevents the use of the usual tie rod to hold the front ends of the track frames in proper spaced relation and the result is that the track frames have a tendency to spread or, conversely, "toe" in at their front ends causing undue wear and strain on the supporting and driving elements for the tracks.

With the above in view it is the main object of this invention to provide a tie rod or equalizer in a simple, durable and efficient form which when applied to the tractor will permit the necessary upward and downward independent 25 play of the front ends of the track frames but will at the same time positively maintain the tracks in proper parallel relationship and prevent the injurious spreading or toeing in aforesaid.

Another object is to provide a structure of this kind comprising a pair of tie elements secured in lateral alignment to the track frames adjacent their frontal ends and laterally extended tie bars connecting the tie elements, 35 these connections including rollers playing in arcuately formed slots so as to permit the necessary vertical movement of the tracks while compensating for the increased diagonal distance between the tie elements and maintaining the tracks in proper spaced relationship.

A further object is to provide a structure as above in which provision is made to permit the torsional or axial play in the parts made necessary by the angular and axial strain existing 45 when one track is raised above the other.

With these and other objects in view the invention resides in the novel construction and arrangement of parts as hereinafter set forth and claimed, reference being had to the accompanying drawings wherein:

Figure 1 is a side elevation of a tractor showing the present invention applied thereto, a part of the track enclosing shield being broken away to expose interior construction.

Figure 2 is an enlarged vertical and cross

section along the line 2—2 in Figure 1, only the supporting channels of the track and the tie and equalizing structure being shown.

Figure 3 is a plan view of the invention, partly broken away and in section showing the angular position of the tie bar when one track (the left) is raised.

Figure 4 is a view similar to Figure 2 but with the frontal tie bar removed and showing the right track channels raised.

Figure 5 is a plan view of a slightly modified structure.

Figure 6 is an enlarged fragmental detail in section of a bolt and spring as shown in Figure 5.

Figure 7 is an enlarged section along the line 7—7 in Figure 2.

Figure 8 is an enlarged section along the line 8—8 in Figure 2.

Figure 9 is a detached side elevation of the 75 rotatable tie element or member alone.

Figure 10 is a front elevation of one end portion of the invention showing a mud guard or shield in place thereon.

Figure 11 is a fragmental front elevation of 80 one end of a modified form of the tie bar and tie member.

Referring now with more particularity to the drawings, in Figure 1 thereof a conventional form of track laying or crawler type tractor is illustrated for purposes of exemplifying one installation of this invention. This form of tractor includes two track assemblies made up of track chains one on each side and one indicated at A, each trained over a rear drive sprocket B and a front idler pulley C journaled at opposite ends of a track frame including spaced and aligned channels D. The track frames thus formed are adapted to swing or pivot on the rear drive axle E whereby the frontal ends F may rise or fall independently when the tracks are traveling over uneven ground or obstructions. The frontal end of the tractor chassis and engine is supported on the track frames by an equalizer leaf spring G seated at its ends in seats H mounted on the channels D just rearwardly of the pulleys C and passing beneath the crankcase J. The foregoing elements and assembly are entirely conventional in form and no invention therefor is herein claimed.

The present invention is made up basically of a pair of tie or connecting members designated generally at 1 and 2 mounted one on each track frame and connected by a tie bar structure 3. The tie member 1 on the right hand track frame 110

(as viewed from the front of the tractor) comprises a rectangular mounting base or plate 5 adapted to seat on the frame channels D and having downwardly turned lips 6 at its ends to grip the upper lateral edges of said channels and being secured in place by bolts 7 in a position just rearwardly of the spring seat H on that side. Formed integrally with this base 5 is a head 8 enlarged and rounded in a vertical plane at its innermost end 9 and terminating in an outwardly extending and tapering reinforcing rib 10. The other tie or connecting element 2 on the left track frame of the tractor likewise includes a rectangular base or mounting plate 11 having downturned lips 12 engaging the upper and lateral margins of the frame channels D on that side and secured in place also just rearward of the spring seat H by bolts 13. A housing 14 is formed on this base 11 at a point slightly off-center in an outward direction thereon and having an inwardly extending and laterally projecting head flange 15 spaced upward from the base. The housing 14 has an axially extended bore 16 and inwardly thereof both the base 11 and inner end portion of the flange 15 are bored out at a larger diameter forming arcuate guideways 17 as shown in Figure 7. The head flange 15 is reinforced by an integrally formed rib 18. A swivel member or casting 19 is mounted by its reduced and rounded stem 20 in the bore 16 of the housing 14 and inwardly of said stem this member has a head portion 21 which is flat on its vertical sides 22 but rounded on its upper and lower faces 23 to fit in and turn freely in the arcuate guide ways 17 aforesaid. At the junction of the stem 20 and head 21 a circular bearing shoulder 24 is formed and is adapted to bear on the inner end of housing 14 and is held thereagainst by a nut 25 turned on the outer threaded end 26 of the stem up against the outer end face of the housing. This nut holds the member 19 against axial displacement in the housing while yet permitting free rotary play and hardened bearing collars designated generally at 27 may be placed between the housing ends and nut 25 and shoulder 24 to prevent undue wear on the housing and swivel member. The nut 25 has the rounded shank 28 turning freely in a rounded depression 29 in the base 11 whereby the flattened head 30 is projected outward to give free access to a wrench for tightening. A set screw 31 is threaded through the shank 28 to lock the nut in place. At its inner end the head portion 21 is enlarged and rounded in a vertical direction as designated at 32.

These rounded and enlarged inner ends 9 and 32 of the head members 8 and 21 have equalizing slots 33 and 34, respectively, cut through from side to side and of arcuate form and extended vertically. These slots are cut on arcs the centers of which both lie inwardly of the respective head members and the slots are thus oppositely curved so that their upper and lower ends turn or curve inwardly as shown and for a purpose to be described. Outwardly of these slots 33 and 34 the head members 8 and 21 also have tie slots 35 and 36 respectively which are elongated in a horizontal direction also for a purpose to be described.

The tie bar structure 3 as here shown is made up of two elongated flat bars 37 and 38 spaced apart sufficiently to receive the heads 8 and 21 between their ends and having their ends 39 and 40 reduced in width, and provided with tie

pins or rollers 41 and 42 extended between the bars and playing freely in the tie slots 35 and 36 respectively, said rollers being journaled on axle pins or bolts 43 and 44 passed through the bar ends. Equalizing rollers 45 and 46 are mounted between the bars 37 and 38 and play in the slots 33 and 34 and are likewise journaled on axle pins or bolts 47 and 48 passing through the said bars. Between these rollers 45 and 46 the bars may be curved downwardly or depressed as shown in order to clear the crank case J of the tractor if necessary. Also the ends 39 and 40 of the bars may be cut out arcuately as designated at 49 in order to clear the adjacent edges of the bases 5 and 11.

It will be readily apparent from the foregoing that the tie bars 37 and 38, equalizing rollers 45 and 46 and tie members 1 and 2 arranged as shown will positively hold the front ends of the track frames in proper even spacing when traveling over level ground. Now as one track frame for instance that on the right is raised or swung upward at its front end in passing over an obstruction or uneven ground the frame channels D on that side are of course raised (Figure 4) together with the tie member 1. The result is the tie bars 37 and 38 swing upward at their right ends and their ends being held against vertical play by the tie rollers 41 and 42 playing in the slots 35 and 36 the equalizing rollers 45 and 46 are caused to travel in the equalizing slots 33 and 34 and the roller on the elevated ends of the tie bars moves down toward the lower end of its slots while the roller at the other ends moves upward. Since the upper and lower ends of these slots 33 and 34 turn and extend inwardly toward the center of the tractor as described this movement of the rollers causes the tie bars to move or be projected endwise in the direction toward the elevated track and the increased distance between the tie members 1 and 2 as measured diagonally and caused by one being elevated above the other is thus compensated for and the curvature of the slots 33 and 34 being properly designed the track frames are still held at the same and desired distance apart as measured in a horizontal plane. The elongated formation of the slots 35 and 36 permits the necessary axial displacement or play of the tie bars 37 and 38 during this action.

As the track frame is raised at its front end as described the tie member 1 on that side is of course swung on an arc centered on the rear axle E and its flat head 8 is thus moved out of its usual vertical plane and a twisting or torsional strain is placed on the tie bars 37 and 38. The swivel member or head 19 however may rotate on its axis in the housing 14 to preserve the proper alignment of the parts, this being the purpose and necessity for a swivel connection in the structure. At the same time as the track frame is raised the tie member on that side is carried on the arc back to a point slightly behind or rearwardly of its usual lateral alignment with the other tie member and an angular strain is put on the tie bars 37 and 38 causing them to swing rearward at their elevated ends as best shown in Figure 3. To permit this action and yet maintain the proper spacing of the bars adjacent the heads 8 and 21 of the tie members the flat vertical sides of these heads may be tapered outwardly from their inner slotted ends toward and somewhat beyond the slots 35 and 36 as indicated at 50 in Figure 4.

3. The axle pins or bolts 43, 44, 47 and 48 may be arranged in the tie bars with sufficient looseness or play to then allow the associated rollers 41, 42, 45 and 46 to stand at proper angles in their associated slots while the tie bars assume an angular position relative to said rollers and slots and the necessary axial displacement and swinging movement takes place. 80
- As an alternative to this arrangement the 10 bolts 43, 44, 47 and 48 may be extended at their ends for some distance, provided with cupped spring washers 51 against the nuts 52 and expansion coil springs 53 braced between the washers and the adjacent tie bar. By this 15 construction the tie bars are normally pressed together against the heads of the tie members but as the tracks rise and fall the springs will give and permit the necessary angular movement and displacement of the bars as aforesaid. In this case the sides of the heads 3 and 41 need not be tapered. 90
- The above action is the same when either of the track frames is raised and will be evident that the track frames will be held in proper 25 spaced relationship and alignment at all times and in all positions. The tie elements may be provided if desired with suitable mud guards or shields one of which is shown in Figure 10 made up of sheet metal in the form of an inverted U-shaped box 54 secured by bolts 55 to the housing flange 15 and having its sides 56 dropped down over the head 21 and adjacent ends of the tie bars 37 and 38 to protect the working parts. The equalizing slots 33 and 34 bearing as they do all the strain in holding the tracks in alignment may be provided with hardened arcuate races 57 (one shown in Figure 9) driven into the slots to prevent undue wear and allow convenient replacement when 35 necessary. 115
- In some installations it may be necessary to vary the arrangement and connection of the tie bars and tie members and one variation is shown in Figure 11 illustrating only the right hand end of the tie bar and associated parts. In this case the equalizing slot 33a instead of being in the head 8a is cut through the enlarged end 58 of the tie bar 37a and of course through the similarly enlarged end of the rear 40 tie bar (not shown). The equalizing roller 45a is then formed of two parts mounted one on each side of the head 8a and held by the journal bolt 47a to play in the slot. This arrangement requires that the slot 33a be cut just 45 oppositely to those hereinbefore described so that its ends turn and extend outwardly instead of inwardly as will be readily understood. 120
- While we have herein set forth a certain preferred embodiment of our invention it is understood that we may vary from the same in minor structural details so as best to construct a practical device for the purposes intended, not departing from the spirit of the invention and within the scope of the appended claims. 50
- 65 We claim:
1. In a tie member for a device of the kind described, a mounting base, a housing formed on the base and having a bore, an overhanging head flange on the housing, the said head flange and base having arcuate depressions, a swivel member having a threaded stem journaled in the housing bore and including a head rounded on two opposite faces to enter the said arcuate depressions, a bearing shoulder formed at the junction of the stem and head and bearing 60 against one end of the housing, a nut threaded on the stem and bearing against the opposite end of the housing, and means for connecting a tie bar to the head of the swivel member. 85
2. In combination with a tractor main frame, a pair of track frames pivoted at their rear ends to the main frame for vertical oscillatory movement at their frontal ends, a tie member mounted adjacent the frontal end of each track frame, one of said tie members comprising a rigid inwardly extended head having an arcuate slot near its inner end, the other tie member comprising a housing, a head swiveled in the housing to rotate in a horizontal plane with its axis at right angles to the track frames, the said head having an arcuate slot in its inner end, a tie bar structure comprising spaced tie bars receiving the said heads between their ends, and rollers journaled between the tie bars inwardly of the ends thereof and playing in the said arcuate slots. 90
3. In combination with a tractor main frame, a pair of track frames pivoted at their rear ends to the main frame for vertical oscillatory movement at their frontal ends, a tie member mounted adjacent the frontal end of each track frame, one of said tie members comprising a rigid inwardly extended head having an arcuate slot near its inner end, the other tie member comprising a housing, a head swiveled in the housing to rotate in a horizontal plane with its axis at right angles to the track frames, the said head having an arcuate slot in its inner end, a tie bar structure comprising spaced tie bars receiving the said head between their 100 ends, and rollers journaled between the tie bars inwardly of the ends thereof and playing in the said arcuate slots, the said heads also having elongated slots outwardly of the said arcuate slots, and rollers journaled between the ends 105 of the tie bars and playing in the elongated slots. 115
4. In combination with a tractor main frame and a pair of track frames pivoted at their rear ends to the main frame for vertical oscillatory movement at their frontal ends, a tie member mounted on each track frame adjacent the frontal end, one of the said tie members comprising a mounting base and a head formed integrally thereof, the said head being extended inwardly of the track frame and having an arcuate vertically elongated slot in its inner end and a horizontally elongated slot spaced outwardly therefrom, the other tie member comprising a mounting base and a housing thereon, 120 a head swiveled in the housing to turn in a horizontal plane on an axis at right angles to the track frame, the said head being extended inwardly and having an arcuate vertically elongated slot adjacent its inner end and a horizontally elongated slot spaced outwardly therefrom, a pair of tie bars extended between the tie members and receiving the heads between their ends, rollers journaled between the ends 125 of the tie bars and playing in the horizontally 130 elongated slots, and rollers journaled between the tie bars inwardly of their ends and playing in the vertically elongated slots. 135
5. In combination with a tractor main frame and a pair of track frames pivoted at their rear 140 ends to the main frame for vertical oscillatory movement at their frontal ends, a tie member mounted on each track frame adjacent the frontal end, one of the said tie members comprising a mounting base and a head formed 145
- 70
- 75

integrally thereof, the said head being extended inwardly of the track frame and having an arcuate vertically elongated slot in its inner end and a horizontally elongated slot spaced outwardly therefrom, the other tie member comprising a mounting base and a housing thereon, a head swiveled in the housing to turn in a horizontal plane on an axis at right angles to the track frame, the said head being extended inwardly and having an arcuate vertically elongated slot adjacent its inner end and a horizontally elongated slot spaced outwardly therefrom, a pair of tie bars extended between the tie members and receiving the heads between their ends, rollers journaled between the ends of the tie bars and playing in the horizontally elongated slots, and rollers journaled between the tie bars inwardly of their ends and playing in the vertically elongated slots, and resilient means for holding the said tie bars together and allowing independent axial and horizontal play thereof.

6. In combination with a tractor main frame, a pair of track frames pivoted at their rear ends to the main frame for vertical oscillatory movement at their frontal ends, a tie member mounted adjacent the frontal end of each track frame, one of said tie members comprising a rigid inwardly extended head having an arcuate slot near its inner end, the other tie member comprising a housing, a head swiveled in the housing to rotate in a horizontal plane with its axis at right angles to the track frames, the said head having an arcuate slot in its inner end, a tie bar structure comprising spaced tie bars receiving the said heads between their ends, and rollers journaled between the tie bars inwardly of the ends

thereof and playing in the said arcuate slots, the said heads being tapered from their inner ends outwardly along the faces engaged by the ends of the tie bars.

7. In combination with a tractor main frame and a pair of track frames pivoted at their rear ends to the main frame for vertical oscillatory movement at their frontal ends, a tie member mounted on each track frame adjacent the frontal end, one of the said tie members comprising a mounting base and a head formed integrally thereof, the said head being extended inwardly of the track frame and having an arcuate vertically elongated slot in its inner end and a horizontally elongated slot spaced outwardly therefrom, the other tie member comprising a mounting base and a housing thereon, a head swiveled in the housing to turn in a horizontal plane on an axis at right angles to the track frame, the said head being extended inwardly and having an arcuate vertically elongated slot adjacent its inner end and a horizontally elongated slot spaced outwardly therefrom, a pair of tie bars extended between the tie members and receiving the heads between their ends, rollers journaled between the ends of the tie bars and playing in the horizontally elongated slots, and rollers journaled between the tie bars inwardly of their ends and playing in the vertically elongated slots, the said rollers being loosely mounted to allow a degree of axial play between the tie bars, and the heads being tapered outwardly from their inner ends along the faces engaged by the tie bars.
